Conn., a corporation of Delaware

Application August 24, 1945, Serial No. 612,481

12 Claims. (Cl. 93—81)

1

This invention relates in general to a machine for manufacturing wound articles, and especially to an improved machine for forming tubes by winding a sheet or strip of any suitable thin material, such for example as paper, for the manufacture of paper shot shells.

An object of the invention is to provide a machine of this character which is efficient, capable of producing wound paper tubes at a rapid rate and one which is economical to build and operate.

The invention consists in certain features of novelty in the construction, combination and arrangement of parts hereinafter fully set forth and claimed and shown in the accompanying drawings in which:

Fig. 1 is a plan view of the improved tube winding machine of this invention including the tube receiving baskets at one end of the machine, and schematically, the feed means for delivering sheets of paper to the winding mandrels of the machine.

Fig. 2 is a front elevation of the winding machine partly broken away to show the winding mandrels and brush.

Fig. 3 is a side elevation partly in section of the left end of the machine.

Fig. 3A is a view similar to Fig. 3 showing the right end of the machine.

Fig. 4 is an elevation of the left end of the machine showing part of the paper feed device.

Fig. 5 is an elevation of the right end of the machine showing the device for distributing the wound tubes into separate baskets.

Fig. 6 is an end elevation partly in section of a star wheel and the mandrel supporting crank arms associated therewith taken in the direction of the arrows 6—6 of Fig. 3.

Fig. 7 is an enlarged end elevation of the cam and cam follower for actuating the crank arms of the mandrels and taken in the direction of the arrows 7—7 of Fig. 3.

Fig. 8 is an end elevation partly in section showing the drive means for the several mandrels and is taken in the direction of the arrows 8—8 of Fig. 3.

Fig. 9 is an end elevation partly in section of the mandrel's brush and wiper blades taken in the direction of arrows 9—9 of Fig. 3.

Fig. 10 is a front elevation partly in section of one set of wiper blades including an element connecting axially the aligned crank rods and showing the tube discharge means. Fig. 10 is taken in the direction of arrows 10—10 of Fig. 9.

2

Fig. 11 is an enlarged end view of one of the wiper blades, crank rod connecting element, and stripper associated therewith, as shown in Fig. 9.

General description

The paper tube winding machine of this invention is of the horizontal bed type having a plurality of rotatable duplex mandrels, a plurality of wiper blades and a single rotatable brush all arranged in cooperatively associated relationship so as to form a continuously rotating cylindrical cage. The terms "duplex mandrel" and "mandrel," as hereinafter used, shall be understood to mean an element on which the paper tube is wound and to comprise two separable mandrel parts supported in axial alignment and adapted to be moved longitudinally into and from end engaging relationship. As the cage rotates, adjacent ends of the mandrel parts are adapted to be joined to form a duplex mandrel, whereupon a paper strip is fed into engagement with the periphery thereof. Suitable means are provided to then move the rotating duplex mandrels radially against the periphery of the rotating brush to press the paper sheet against the mandrel thereby initiating the winding of the tube. A wiper blade is then moved into engagement with the partially formed tube to complete the winding operation, the mandrel being, in the meantime, withdrawn from engagement with the brush. At the end of the winding operation, the duplex mandrels are separated longitudinally, thereby stripping off the wound tube which falls down onto supporting means in the bottom of the machine in longitudinal alignment with a tubular discharge passage in one end thereof. Thereafter a suitable pusher engages the wound tube and moves it through the tubular discharge passage out into a distributing device. The tube forming operation is thus continuous and uninterrupted from the time the paper sheet is fed to a mandrel until the completely wound tube is discharged from the machine; moreover, a plurality of tubes are being wound simultaneously by the continuously rotating cage.

Frame structure

Referring to Figs. 1 and 2, the machine frame comprises a substantially rectangular box structure indicated generally at 15 and formed of castings or forgings bolted or otherwise secured together to form a rigid structure, the length of which is, roughly, three times its width, its height being, roughly, one and one half times its width. The box frame 15 is supported in a substantially

horizontal plane by suitable legs 16 at opposite ends of the frame. The front of the machine is provided with hinged doors 17, one door being adjacent each end of the machine to give access to the mandrel driving mechanisms which are located at opposite ends of the machine. Between the two ends of the machine are hinged covers 18 and 19 which are adapted to give access to the paper tube winding mechanism, including the brush and the wiper blades hereinafter described. At the right end of the machine, as viewed in Fig. 1, are suitable discharge bins or baskets indicated generally at 20 for receiving the wound tubes, suitable distributing means 22 being provided, as hereinafter described, to discharge the tubes into the baskets 20.

The left and right end walls 26 and 27, respectively, of the frame, provide suitable supporting means for the bushings 28 of the main drive shaft 29 and for the bushed bosses 30 and 30' of a compound axle 32 which is adapted to drive the mandrels and the brush of the tube winding cage, as hereinafter described. Intermediate the end walls 26 and 27, and in spaced parallel relationship therewith, are transverse partitions 33 and 34, each of which is a rigid part of the frame structure and is adapted to provide supporting means for an intermediate bushing 35 of the main drive shaft 29. Each partition is provided centrally with an enlarged aperture 36 and 37, respectively, which constitutes a bearing for an element of the cage, as described below.

The tube winding machine is adapted to be operated in conjunction with a paper sheet delivering and adhesive applying machine which is schematically shown at 23 of Fig. 1, the tube winding machine being driven in synchronism with the paper delivering machine by drive means, such as the chain 24 and sprockets 25 and 25', the latter being secured to the main drive shaft 29 of the tube winding machine, as shown in Fig. 3A. It will be understood, however, that the drive shaft 29 may be driven from an independent power source.

Drive mechanism

The machine is provided at its opposite ends with duplicate drive mechanism for performing certain operations, and hence, for the sake of brevity, a description of only one of each duplicated structure will be given.

The main drive shaft 29 is rotatably supported by bushings 28 substantially transversely centrally disposed in the lower part of the frame. Secured at opposite ends of the shaft 29 are drum cams 38 having grooves 38', each adapted to receive a cam follower 39 attached to the bottom of a carriage 40. Each carriage, as shown in Fig. 3, 3A, and 8, comprises a substantially rectangular block adapted to be slidably supported in a horizontal plane by a pair of spaced parallel guide rods 42, 420 and 43. The guide rod 43 of each carriage is secured at its opposite ends in the end wall and in the partition at its respective end of the frame. The guide rod 42 of the carriage at the left end of the machine is reciprocably supported at its opposite ends in bushed apertures of its respective end wall 26, and partition 33, and is adapted to be locked to the carriage by suitable fastening means, such as clamp 42'. The guide 420 for the carriage 40 at the right end of the machine comprises a tubular member which is fastened securely to the carriage and is also reciprocably mounted at its opposite ends in bushed apertures of its respective

end wall 27, and partition 34. Each reciprocably mounted guide rod 42 and tube 420 respectively is secured in a longitudinal aperture 44 in one side of its respective carriage. The opposite side of each carriage is provided with a slot 45 which is substantially rectangular in cross-section to slidably accommodate suitable flats 46 which are provided on the top and bottom surfaces of the respective fixed guide rods 43. As shown, the fixed guide rods 43 are extended through their respective partitions 33 and 34 of the frame and are adapted to support brackets 49 which are adjustable longitudinally on the extended ends 43' of the fixed rods 43. Each bracket has an arcuate relatively thin stiff apron member 50 riveted or otherwise secured to the flanged portion 49' thereof. It is the function of the aprons 50 to support the wound tubes when they are stripped off of the duplex mandrels, and hence, the aprons 50 are supported by the brackets 49 for adjustment longitudinally on the extensions 43' of the fixed guide rods 43 in order to adapt the machine for winding tubes of various lengths.

It will be clear that when the main drive shaft 29 rotates, the drum cams 38 will reciprocate the carriages 40, the latter being guided by the fixed guide rods 43 and the reciprocable guide rod 42 and tube 420. The latter are reciprocated in synchronism with the movement of the carriages for effecting the discharge of the wound tubes, as described below. Each carriage is also shown provided with an upstanding projection 47 having at one end a transverse groove 48 which is adapted to engage and actuate one of the separable parts of a duplex mandrel for performing the stripping operation as hereinafter described.

Tube winding cage

The term "cage," as used herein, shall be understood to designate a unitary cylindrical structure which comprises the tube winding mandrels, the brush, the wiper blades, the tube strippers and the associated drive mechanism for actuating the mandrels and wiper blades, the cage being rotatable as a unit continuously in the frame about the horizontal compound axle 32.

The main drive shaft 29 drives the compound axle 32 of the cage through the sprocket 52, chain 53, idler 54, and sprocket 55, the latter, together with a gear 56, being keyed to the reduced end of an internal shaft 57 of the compound axle 32. As shown in Fig. 4, the gear 56 is part of a speed reduction gear train including the back gears (not shown) which are mounted on a stud shaft 59; and a gear 60 which is keyed to the end of a sleeve 62 of the compound axle, the sleeve 62 being rotatably supported on the left end of the internal shaft 57 by suitable bearings 63, as shown in Fig. 3. A similar sleeve 62' is supported by bearings 63' on the right end of the shaft 57, as shown in Fig. 3A. The outer end of each sleeve 62 and 62' is rotatably mounted in a bushing 64 and 64', respectively, which in turn is carried in a flanged bushing 65, 65', respectively, fixedly secured in the bosses 30 and 30' formed on the inside of the end walls 26 and 27 of the frame. The inner end of each sleeve 62 and 62' is inserted into and keyed, as shown, to the hub portion 66 and 66' of relatively heavy discs or turrets 67 and 67' which are supported in the vertical planes of the respective partitions 33 and 34, the peripheries of the turret discs making a nice rotating fit in the apertures 36 and 37 of the fixed partitions 33 and 34, respectively. It will be clear

that the internal shaft 57 of the compound axle 32 will be rotated relatively rapidly, whereas the exterior sleeves 62 and 62' will rotate more slowly.

The shaft 57 carries a cylindrical brush 68 which is located between the rotatable turrets 67 and 67', suitable spacer collars 69 being secured on the shaft 57 between the respective ends of the brush and the adjacent faces of the respective turrets.

Fixedly secured to the flanged bushing 65 in the left end of the machine, see Fig. 3, by a set screw, is a cam 70 which, as shown in detail in Figs. 6 and 7, has a cam groove 72 in its inner face to receive cam followers or rollers 73 which are carried on the ends of suitable crank arms 74. The opposite end of each crank arm is provided with a hub 75 in which is keyed one end of a crank rod 76. Each crank arm 74 also embodies a nose portion 77 for the purpose hereinafter described.

The crank arms 74, of which there are six in the embodiment shown, are supported by means of their respective crank rods 76 adjacent the outer face 790 of a rotatable star wheel 79, the hub 80 of which is keyed to the sleeve 62. Each crank rod 76 extends through and is rotatably supported in a bushed aperture 82 in one of the "points" of the star wheel 79. The scallops between the points of the star wheel provide clearance for the longitudinal movement of the spindles 85 to be presently described. A mandrel actuating lever arm 83 is keyed at one end to each crank rod 76 adjacent the inner face 791 of the star wheel 79. The opposite end of each lever arm 83 is provided with a bushing 84 to rotatably support the outer end of a spindle 85 which is adapted to support one part 95 of a duplex mandrel 950, hereinafter termed a "mandrel part" and to slide longitudinally in its bushing 84. The outer or rear end of each spindle 85 is provided with a tapped hole 86 to receive an adjustable stud 87 having a lock nut thereon and a smooth rounded head 88. During the operation of the machine and, in particular, that point in the cycle of operations when the mandrel parts 95 and mandrel supporting spindles are moving into normal operating position, the rotation of the star wheel 79, relative to the fixed cam 70, will cause the nose portion 77 of each crank arm 74 to cammingly engage the rounded head 88 of its respective spindle so as to positively move the spindle inwardly or to the right, as shown in Fig. 3, thereby forcing the axially aligned mandrel parts 95 of a duplex mandrel 950 into interlocking engagement. The latter effect is accomplished by providing one mandrel part with a teat 951 at its end; and the corresponding mandrel part with an axial aperture or socket 952 at its end to receive the teat of its corresponding mandrel part.

The crank rods 76 at the right and left ends of the machine extend inwardly, as shown in Figs. 3 and 10, and pass through suitable bushed apertures 89 which are circumferentially spaced about the perimeters of the turrets 67 and 67'. The ends of these crank rods project slightly beyond the oppositely disposed faces of the turrets and are flattened, as at 90, to provide means for connecting the axially aligned crank rods at opposite ends of the machine with intermediate connecting elements of the wiper blades so as to form a unitary cage.

Each mandrel part supporting spindle 85 is provided with a pulley 92 formed integrally at the inner end of the spindle; and an axially

tapered aperture 93 to receive the tapered shank portion 94 of the mandrel part 95. A cotter pin 96, or other fastening means, may be provided to hold the shank of the mandrel part in the aperture 93. To remove the part from its spindle it is only necessary to withdraw the cotter pin 96 and insert a drift pin in a diametrical aperture 97 of the spindle to start the shank 94 from the tapered aperture 93.

The end of each mandrel part 95 adjacent its shank portion 94 is rotatably supported in the bushed and flanged end 98 of a lever arm 99, each of which corresponds to one of the lever arms 83 of the star wheel 79. The opposite end of each lever arm 99 is carried by and keyed to one of the crank rods 76 at the adjacent face of its respective turret. The diameter of each flange 98 is such that the flange will at all times span its respective aperture 100 in the turret, there being six apertures 100 alternately spaced between the circumferentially spaced bushed apertures 89 of each turret. As shown, each mandrel part extends through one of the apertures 100 of one of the turrets and has sufficient clearance therein for transverse movement.

The means for rotating the mandrel parts at the left end of the machine comprises a plurality of pulleys 102, 103, and 104, mounted on the outer face 330 of the partition 33, see Figs. 3 and 8, the pulleys 102 being supported on stud shafts fixed to the partition 33, the pulley 103 being carried on one arm of a pivoted bell crank lever 105, which is spring biased by the spring 106 to take up slack in an endless V-belt 107. The pulley 104 is secured by a set screw to a shaft 108 which is rotatably supported at its opposite ends in bushings in the respective partitions 33 and 34 of the frame and which carries a sprocket 108 connected by a chain 109 to a sprocket 110. The latter is keyed to a second stud shaft 111 which is mounted on a bracket of the frame and provided with a spur gear 112 which meshes with a gear 113 keyed to the main drive shaft 29. The endless V-belt 107 is disposed around the drive pulleys 102, 103 and 104, as shown in Fig. 8, and over the outer rims of the spindle pulleys 92. As shown, the belt 107 rotatably engages five of the pulleys 92 simultaneously. It will be seen that when a pulley has been carried to its lowermost position by the rotating cage, it will be out of engagement with the belt and, hence, will not be rotated. In this manner, each pulley is successively disengaged from the belt 107 and during this interim, its rim is adapted to engage in the transverse groove 48 of its respective carriage 40. The motion of the latter is synchronized with the rotation of the cage so as to pick up each pulley as it approaches the bottom of the tube winding cycle and carry the pulley, its spindle 85 and respective mandrel part 95 to the left, as shown in Fig. 3, the spindle and mandrel part sliding through their respective bushed apertures of the arms 83 and 99. This longitudinal movement of each mandrel part is adapted to strip a wound tube off of a duplex mandrel in the manner hereinafter described.

From the foregoing description it will be clear that each mandrel part has a compound motion during its cycle of operation. Thus, as the cage rotates, the star wheel 79 and turret 67 rotate in synchronism, being connected by the common sleeve 62 and the several circumferentially spaced crank rods 76. The rotation of the star wheel moves the cam followers 73 around the cam groove 72 of the fixed cam 70, whereupon the crank

árms 74 of the crank rods 76 are oscillated, thereby imparting a similar oscillating motion to the lever arms 83 which carry the rotatable spindles 85. Moreover, the lever arms 99 which are keyed to the crank arms 76 adjacent the turret 67 impart a similar oscillating motion to the mandrel parts supported in the spindles. Consequently each spindle and its respective mandrel part moves outwardly and inwardly radially simultaneously with respect to the axis of the cage, the enlarged apertures 100 of the turret 67 providing clearance for this transverse movement of the mandrel parts. Further, each mandrel part is being rotated on its longitudinal axis as described above, and is adapted to be moved longitudinally by its respective carriage during a part of the tube winding cycle of the cage.

The description thus far of the fixed cam 70, star wheel 79, crank rod 76, mandrel parts 95, lever arms for supporting the mandrel parts and the mandrel part rotating and reciprocating means, has related to the mechanism at the left end of the machine, as shown in Fig. 3. Fig. 3A shows similar mechanism at the right end of the machine. It will be noted, however, that a fixed cam 70 is not shown for actuating the crank arms 74, a suitable collet 700 being shown in its place. It has been found that by the use of an intermediate connecting means between the crank rods, a second cam 70 is not necessary for imparting oscillating motion to the mandrel parts at the right end of the machine. It will be understood, however, that the collet 700 may be readily replaced by a fixed cam 70, if preferred. Further, the pulleys and belt for rotating the mandrel parts at the right end of the machine are driven from the shaft 103 which extends through to the right end of the machine, the pulley 104 being keyed to the end thereof.

In the absence of a fixed cam 70 at the right end of the machine, the crank rods 76 at this end are connected to the cam actuated crank rods at the left end of the machine by interconnecting members which comprise elements of the tube wiper blades.

Referring to the drawings, Fig. 10 shows one of the six wiper blades, and an element associated therewith, for connecting one pair of axially aligned crank rods 76. This is but one connecting element of six such elements for connecting respective pairs of axially aligned crank rods. As described above, the projecting ends of the crank rods are provided with flattened surfaces 90, which adapt each end of a crank rod to make a snug fit in a substantially rectangular slot 114 in opposite ends respectively of one of the connecting elements or bars 115 of a wiper blade assembly, each flattened end of a crank rod being secured in its slot by a pin 116. As a consequence of this construction the rotation of the crank rods at the left end of the machine is transmitted to the crank rods at the right end of the machine and the supporting and operating mechanism for the mandrel parts at opposite ends of the machine are thus joined together and rotate as a unit or cage about the axle 57.

Each end portion or knuckle 115' of a connecting bar 115, see Fig. 11, is substantially rectangular in cross-section, whereas the portion between the ends 115' and constituting the major length of the bar, is half round in cross-section, as shown in Fig. 9. This half round construction is to enable the bar 115 to clear the bristles of the cylindrical brush 68 as shown in Fig. 10.

Each knuckle 115' embodies an arm 117 which

extends transversely to the bar 115 and is provided with a bushed aperture 118 at its free end. An upstanding substantially vertical web 119 is formed integral with each arm 117 and is provided with a transverse aperture 120 to receive a pivot pin of a stripper member, hereinafter described. An aperture 122 projects through the knuckle 115' adjacent the web 119 and in a plane substantially parallel to the vertical plane of the web. This aperture is adapted to support a post 123 which is secured in the aperture 122 by a pin 124. The post is bent over at substantially right angles to its upper end to provide a support for one end of a coil spring 125.

15 Pivotedly supported between each arm 117 on pins 126 in the bushed apertures 118 are the end members 127 of a wiper blade indicated generally at 128. The wiper blade comprises an elongated bar substantially wedge-shaped in cross-section and provided with a relief recess along its thin edge in which is secured a rubber wiper 128'. In the present embodiment each end member 127 is formed integral with an end of the wiper blade 128 and embodies an axially projecting pin 129 and a transversely extending rocker arm 130, the latter having a bushed aperture to support a rotatable cam follower 132, as shown in Fig. 10. The latter is adapted to be held in engagement with a horseshoe shaped cam 133 by the coil spring 125 which is connected to the post 123 and to the pin 129 of the pivoted wiper blade 128. The cam 133 is shown fixedly secured to the transverse partition 33 at the left end of the machine. It has been found that a single cam will suffice to provide the proper movement to the wiper blades during the rotation of the cage but it will be evident that the machine is readily adapted to include a second fixed cam on the transverse partition 34.

40 Pivotedly supported on the web 119 of the arm 117 by a pin 135 is a stripper element 136 comprising a substantially keystone shaped member having a transversely disposed sleeve at its larger end. The working end of the sleeve is tapered 45 as at 136'. The inside diameter of the sleeve is slightly less than the outside diameter of a wound tube but is of sufficient diameter to enable the mandrel parts of the cage to pass freely therethrough. Throughout the operations of 50 winding and stripping a wound tube from the mandrel parts, the latter remain within the pivotally mounted strippers 136 although in the actual stripping operation the ends of the mandrel parts are retracted by the reciprocating carriages 55 40 below the working ends 136' of the sleeves, as shown in Figs. 3, 3A and 10.

Referring to Fig. 9, the paper is adapted to be fed to a rotating duplex mandrel from the back of the machine through suitable guide plates 137. 60 At the instant the paper engages the rotating duplex mandrel, the mandrel is in a position relative to the periphery of the brush such that the bristles of the brush press the paper against the periphery of the mandrel to initiate the paper tube winding operation. The respective wiper blade 115 is, at this time, held out of engagement with the paper by the fixed cam and cam follower mechanism described above. However, as soon as the continuously rotating cage has carried the cam follower 65 132 out of contact with the fixed cam 133, the spring 125 is enabled to draw the wiper blade 128' upwardly against the wound tube. The wiper blade thus serves both to remove excess paste from the tube and to iron the several convolutions 70 of the wound paper. This action of the wiper

75

blades continues for substantially a quarter of one revolution or cycle of the cage, whereupon the wiper blade cam follower 132 again engages the fixed cam 133 to hold the wiper blade out of contact with the wound tube.

Tube stripping and discharging mechanism

A completely wound tube is stripped from a duplex mandrel by withdrawing each mandrel part axially out of an end of the wound tube, the latter being held against longitudinal movement with respect thereto by engagement with the ends 134' of the stripper elements 134, as clearly shown in Fig. 10.

The stripped tube drops from the mandrel down onto the aforementioned arcuate aprons 50 which are adapted to engage and support the opposite ends of the tube. As shown in Fig. 9, a tube which is supported on the aprons 50 lies in the path transversed by the wiper blade bar 128 during the rotation of the cage and, hence, the bar 128 engages and moves the stripped tube up the inclined aprons 50 and over the rearwardly extending free ends 50' thereof. The tubes then fall down onto a pair of spaced parallel upwardly projecting substantially flat guide fingers 138 which are riveted or otherwise fastened at their lower ends to elements of the tube discharging means.

The tube discharging element at the left end of the machine embodies a U-shaped trough 139 having an upturned lip portion at its outer end to which the finger 138 is fastened; and an apertured flange 139' by which the trough is fastened securely and substantially perpendicular to the adjacent wall 331 of the partition 33. The aperture of the flange and the longitudinal axis of the trough 139 are adapted to be in axial alignment with the reciprocable guide rod 42 of the carriage 40 at the left end of the machine. The inner end of this guide rod 42 is shown provided with a tapered nose 140 having a flange 140'. The tapered nose is adapted to enter into the adjacent open end of a stripped tube lying in the U-shaped trough 139, as the rod moves forwardly or to the right, see Fig. 10, until the flange 140' of the rod 42 positively engages an end of the tube whereupon the tube will be pushed to the right, as seen in Fig. 10.

The tube discharge element at the right end of the machine also embodies a U-shaped trough 142 having an upturned lip portion at its outer end to which a finger 138 is fastened; and an apertured flange 142'. The latter is adapted to be fastened securely to the flange 143 of a coupling 144 which is threadedly secured on the adjacent end of the reciprocable carriage guide tube 420 at the right end of the machine, the aperture of the flange 142' and the longitudinal axis of the trough 142 being in axial alignment with the reciprocable tube 420. The internal diameter of the tube 420 is slightly greater than the outside diameter of a wound paper tube so that a paper tube may be readily moved therethrough, as hereinafter described. The coupling 144 is shown provided with an internal annular groove 145 in which is mounted a resilient washer 146.

Thus, as a wound tube is stripped from its mandrel parts by retraction of the carriages 40 and drops over the free ends of the aprons 50, the opposite ends of the tube will be supported in the troughs 139 and 142, respectively. Then, as the carriages 40 move inwardly simultaneously, both the guide rod 42 and guide tube 420 move toward each other, whereupon the flanged nose 140 of the rod 42 telescopes the wound tube into the ap-

proaching tube 420. At the end of the stroke of each carriage, the wound tube will have been telescoped substantially its entire length into the tubular guide 420 and thereafter as the carriages

5 40 again recede or move apart, the guide rod 42 will be withdrawn from engagement with the end of the tube and the guide tube 420 will carry the telescoped tube to the right out of the path of the tube being stripped from the next succeeding duplex mandrel. The resilient washer 146 of the coupling 145 will provide sufficient friction on the surface of the telescoped tube to hold the latter in the guide tube 420. When the carriages again move inwardly the next succeeding stripped tube

15 will be pushed into engagement with the end of the telescoped tube and hence push it out of the extreme right end of the guide tube 420.

At the right end of the machine, see Fig. 5, is a tube distributor for delivering the discharged

20 tubes consecutively and in parallel relationship to suitable baskets 20. The distributor is a substantially rectangular open frame member, indicated generally at 22, see Fig. 2, which is pivotally mounted on its transverse axis on a substantially horizontal shaft 148 fixed to the end wall

25 21 of the machine. The frame comprises transversely extending angle bars 149 which constitute baffles to guide the free fall of the tubes. The angle bars also serve as brackets to support

30 suitable plates over which the tubes may roll in passing from one set of baffles to another. It will be noted that the baffles and tube supporting plates in one half of the frame are oppositely disposed to those in the other half of the frame.

35 At each end of the frame 22 is a pivoted ladder 152 and 152', respectively, comprising spaced parallel side members connected by transversely arranged steps 154, each comprising a trough shaped member and oppositely inclined to the

40 preceding and next succeeding step. Thus, as the tubes roll off of the supporting blades 150 of the tilted frame, they transverse the steps of the ladder until they drop from the last step into a basket.

45 The frame 22 is pivotally mounted so that it may be tilted to deliver tubes, first, to the ladder 152 at the left of the central discharge tube 420, see Fig. 5, until its respective basket is full, and then to the ladder 152' and its respective basket

50 at the right of the central discharge tube without interruption in the continuous operation of the tube winding and delivering operations, a full basket being removed and replaced by an empty one while the second basket is being filled.

55

Operation

The operation of the machine may be briefly reviewed as follows: When the paper feeding machine is started, the sprocket and chain connection between the paper feeding machine 23 and the tube winding machine will drive the latter in synchronism with the former. The tube winding cage begins to rotate slowly, continuously carrying the mandrels 950 and wiper blades 128 through complete revolutions or tube winding cycles in a counterclockwise direction, as viewed from the right end of the machine. Simultaneously, the mandrels 950 and brush 68 are rotated at relatively high speeds, the brush rotating counterclockwise and the mandrels clockwise. The carriages 40 are reciprocated longitudinally in synchronism with the rotating cage. Moreover, as the cage rotates, the mandrels 950 are being oscillated radially with respect to the cylindrical brush 68 by the crank arms 74, fixed cam 76 and

65

70 75

lever arms 93-99, described above, while the wiper blades 128 are being oscillated into and from engagement with the mandrels by their respective fixed cams 133, rocker arm 130 and cam followers 132. Thus, as a strip of pasted paper is being fed through the guides 137 into juxtaposition to one of the duplex mandrels 950, the latter will move radially into engagement with the brush 68 so that the edge of the paper strip will be nipped between the brush 68 and mandrel 950 and pressed by the brush against the periphery of the mandrel whereupon the latter picks up the paper to initiate the winding operation. Thereafter the wiper blade 128 associated with this particular duplex mandrel will move into engagement with the wound tube to remove excess paste therefrom and to iron down the convolutions. The tube T is held by the duplex mandrels against the rotating brush only during a relatively short period of the cycle, whereas the wiper blades 128 remain in contact with the tube for substantially a quarter of the revolution of the cage. At the end of this time, which corresponds to the nine o'clock position of the mandrel, the wiper blade is withdrawn, as clearly shown in Fig. 9. In the interim, sheets of paper have been fed and wound onto the next two succeeding duplex mandrels and a third sheet of paper is about to be fed onto the third succeeding mandrel of the continuously rotating cage. When a wound tube approaches the bottom of its cycle (the six o'clock position) the pulleys 92 of the spindles 85 of the respective mandrel parts 95 are carried out of engagement with the belt drive means 107 and, hence, cease to be rotated and thereafter are carried into the transverse grooves 48 of the respective reciprocating carriage 40 which move the spindles 85 longitudinally to the left (Fig. 3), and to the right (Fig. 3A), respectively, thus drawing the respective mandrel parts 95 apart and stripping the wound tube T therefrom. The wound tube then drops down and is supported at its opposite ends on the arcuate fixed aprons 50. As the cage continues to rotate, the tube is picked up by the adjacent portion of its respective wiper blade 128 and carried up over the ends of the aprons 50 from which it drops down freely into the two troughs 139 and 142. The carriages 40 have now reversed their direction of travel and move toward each other, whereby the reciprocable guide rod 42 of the carriage at the left end of the machine engages and telescopes the wound tube T into the approaching guide tube 420 of the opposite carriage. As the carriages 40 again recede, the telescoped tube T is carried out of the path of the next succeeding tube which is being simultaneously stripped from its respective mandrel parts 95. The telescoped tube T is ejected from the guide tube 420 by the next succeeding tube as hereinabove described. As the separated mandrel parts approach the three o'clock position in their cycle of rotation, the teat 951 of one mandrel part is moved into the socket 952 of the adjacent mandrel, this interlocking of the adjacent ends of the mandrel parts being effected by engagement of the nose portion 77 of the respective crank arms 74 with the rounded heads 88 of the respective spindles 85.

What is claimed is:

1. A tube winding machine comprising a continuously rotating cage and means to rotate said cage in a tube winding cycle, said cage embodying a compound axle rotatably mounted in a substantially horizontal plane and comprising rotatable sleeves and a shaft rotatable within said sleeves, spaced parallel star wheels secured to

said sleeves at opposite ends of said axle, spaced parallel turrets secured to said sleeves intermediate said star wheels, a cylindrical brush secured to said shaft between said turrets, a plurality of horizontally disposed spaced parallel crank rods connecting said star wheels and turrets, a plurality of duplex mandrels supported by said crank rods between said turrets and in spaced relationship around said brush, means for rotating each duplex mandrel on its longitudinal axis during the rotation of said cage, means to oscillate each mandrel to and from the brush during the rotation of said cage, a plurality of wiper blades supported by said crank rods between said turrets and in spaced parallel relationship to said mandrels, means to oscillate each wiper blade toward and away from its respective mandrel; carriages reciprocably mounted in juxtaposition to said cage, each carriage having an element arranged to engage a mandrel part during the rotation of said cage; and means for reciprocating said carriages simultaneously away from and toward each other to separate the mandrel parts of a duplex mandrel so as to strip a formed tube therefrom and to eject the stripped tube from said machine respectively.

2. Apparatus for the winding of tubes from sheet material comprising a brush mounted for revolution on a fixed axis, a cage surrounding said revolving brush, means for continuously rotating said cage at an angular speed different from the angular speed of said brush, a plurality of winding mandrels and mandrel supports mounted in said cage, and means for shifting said mandrels radially toward and away from said brush as said cage is rotated.

3. Apparatus according to claim 2 in which the mandrel shifting means comprises a fixed cam, an arbor carrying a crank provided with a cam follower, a pair of arms secured to said arbor, and a mandrel support associated with said arms.

4. Apparatus according to claim 3 in which said mandrel support is slidable in the direction of its length in bearings in said arms, and is provided with a pulley adapted in certain longitudinal positions of said mandrel support and rotational positions of said cage to be engaged and driven by a driving belt.

5. Apparatus according to claim 4 in which an end portion of said mandrel support is engaged by a part of said arbor crank to temporarily lock the mandrel support at one extreme of its longitudinal movement.

6. Apparatus according to claim 5 in which the mandrel support is moved to its extreme position by its engagement with a tail on said crank.

7. Apparatus for the winding of tubes from sheet material comprising a brush mounted for revolution on a fixed axis; a cage surrounding said revolving brush; means for continuously rotating said cage at an angular speed different from the angular speed of said brush; a plurality of winding mandrels and mandrel supports mounted in said cage; means for shifting said mandrels radially toward and away from said brush as said cage is rotated; said mandrel shifting means comprising a fixed cam, an arbor carrying a crank provided with a cam follower, and a pair of arms secured to said arbor; said mandrel supports being associated with said arms, slidably in bearings on said arms, and provided with pulleys adapted in certain longitudinal positions of said mandrel supports and rotational positions of said cage to be engaged and driven

by a driving belt; and means for reciprocating said mandrel supports comprising a member adapted for engagement with a peripheral portion of said pulleys, a cylindrical box cam, and a cam follower supported for rectilinear reciprocatory movement.

8. Apparatus for the winding of tubes from sheet material comprising a brush mounted for revolution on a fixed axis; a cage surrounding said revolving brush; means for continuously rotating said cage at an angular speed different from the angular speed of said brush; a plurality of winding mandrels and mandrel supports mounted in said cage; and means for shifting said mandrels radially toward and away from said brush as said cage is rotated, said mandrel shifting means comprising a fixed cam, a pair of spaced and longitudinally aligned arbors in opposite ends of the apparatus associated with each of said mandrels, a connecting member parallel to and adjacent said brush rigidly joining adjacent ends of the arbors of each pair, a crank carried by an arbor of each pair, a cam follower carried by each crank and engaged by said cam, a pair of arms projecting from each arbor, and mandrel supports associated with said arms.

9. Apparatus according to claim 8 in which a wiper blade is pivotally held in arms integral with said connecting member, whereby said wiper blade is bodily shifted with the mandrels in said mandrel supports toward and away from said brush.

10. Apparatus according to claim 9 in which the pivotal movement of the wiper blade on said connecting member is controlled by a fixed cam.

11. Apparatus for the winding of tubes from sheet material comprising a brush revolving about a fixed axis, a cage surrounding and coaxial with said brush and mounting a plurality of counter-part mandrel halves, means for continuously revolving said cage, means for shifting said mandrel halves radially with respect to said brush, means for intermittently revolving said mandrel halves, means for reciprocating said mandrel halves toward and from each other, and tube removing means associated and reciprocating with said mandrel reciprocating means.

12. Apparatus according to claim 11 in which the tube removing means comprises a push rod associated with one mandrel reciprocating means and adapted to thrust a tube endwise, and a tubular member associated with the second mandrel reciprocating means adapted to receive the tube advanced by said push rod.
